ARTICULATED METAL TAPE FOR
VENETIAN BLINDS

William P. Cameron, Philadelphia, Pa., assignor
to Cameron Metal Tape Company, Inc., Phila-
delphia, Pa., a corporation of Delaware

Application February 9, 1934, Serial No. 710,542

3 Claims. (Cl. 156—17)

This invention relates to improvements in Venetian blinds, and the principal object of the invention is to provide a novel form of articulated metal tape for uniting the elements of the blind.

5 The invention further resides in certain novel structural details and arrangements hereinafter set forth and illustrated in the attached drawing, in which:

Figure 1 is a fragmentary view in perspective of 10 a Venetian blind equipped with a metallic tape made in accordance with my invention;

Figs. 2 and 3 are detached views in perspective of elements of the blind;

Figs. 4 and 5 are detached views in perspective 15 of elements of the tape, and

Fig. 6 is a fragmentary end view showing the tape in both the extended and folded conditions.

With reference to the drawing, the slats of the Venetian blind are indicated by the reference 20 numeral 1. In the present embodiment, each of the slats is provided at its ends with projecting metallic plates 2, which are individually clamped to the slats by means of a clamping element 3 in the form of a plate having flanges 4 which 25 project through the slats 1 and through apertures 5 in the plate 2 and are turned over against or riveted to the outer face of the latter plate. The extending portions of the plates 2 are provided at opposite sides with openings 6, the flat 30 sides of which lie closely adjacent to the side edges of the plate to form pintles to which the elements of the metallic tape forming the subject of the invention are connected.

The tape in a preferred embodiment consists 35 of a series of links pivotally connected together and to the slats 1 through the medium of the extension plates 2. The links comprise two forms designated respectively 8 and 9. The links 8 are bifurcated at one end, and the bifurcations in 40 assembly are turned over to form eyes 10, 10 embracing the respective pintles 7 of the extension plates 2. The links 9 at one end are formed with a central projection which in assembly is formed into an eye 11 also embracing 45 the pintles 7 intermediate the eyes 10, 10 of the links 8. The other end of the link 9 is provided with two apertures 12 and 13 providing therebetween a pintle 14 which in assembly is embraced by an eye 15 formed at the adjoining ends 50 of the links 8. The terminal ends 9a of the link's 9 which project beyond the pintles 14 engage the sides of the adjoining links 8 and thereby form stops limiting the relative movement of the links about the pintles 14. Preferably the apertured ends of the links 9 are slightly offset or

bowed to permit the links when extended to lie in substantial alignment.

In assembly, the links are connected to the slats as illustrated in Fig. 1, with the ends 9a of the links 9 at the inner side of the tape so that when the slats are moved together, the tape may fold inwardly between the slats, as illustrated. It will be noted by reference to Fig. 6 that when the links are fully extended, the ends 9a of the links 9 by engaging the inner faces of 10 the links 8 retain the links in a slightly angular relation so that when the adjoining slats are brought together, the links will positively fold inwardly, and there is no tendency for the links to remain in the extended position. The links 15 are prevented from folding outwardly as previously set forth. In the fully folded position, the links lie substantially flat between the slats and against the faces of the extension plate 2 so that the slats are permitted to lie close together 20 in face-to-face relation.

In a blind made in accordance with my invention, the usual means may be provided for drawing the slats progressively upwardly from the bottom of the blind, and the operation of 25 the blind is in accordance with the usual practice. The metal tape forming the subject of my invention is intended to entirely replace the ordinary fabric tape used to connect the slats in the standard forms of Venetian blind. The metal 30 tape is considerably more compact than the fabric, is more durable, and is practically invisible when the screen is in the folded or elevated position. It will be noted that the links of which the metal tape is formed may readily be formed 35 by stamping from sheets, and the operation of assembly is both relatively inexpensive and simple.

I claim:

1. A metal articulated tape for Venetian blinds 40 and the like comprising two sets of links arranged in end-to-end relation with the links of one set alternating with the links of the other set, one end of each of said links being formed for pivotal connection directly with the slats of the blind and the opposite ends of the links being formed for 45 pivotal connection to each other, and means at the latter ends of the links for restricting to one direction only the folding movement of the links from the extended position.

2. In a Venetian blind, the combination with 50 a plurality of slats, of an articulated tape connecting said slats and comprising between each adjacent pair of slats a pair of rigid links hinged together at one end and hingedly connected at 55

their opposite ends to the respective slats, said links being adapted to fold inwardly between the slats when the latter are brought together, and means for preventing folding of said links in the opposite direction.

3. In a Venetian blind, the combination with a plurality of slats, of an articulated tape connecting said slats and comprising between each adjacent pair of slats a pair of links hinged together and adapted to fold inwardly between the

slats when the latter are brought together, apertures in one of said links forming therebetween a pintle pin, and an extension on the other of said links embracing said pintle, the extremity of said apertured link when the links are extended engaging the inner face of the other link and preventing outward folding of said links when the slats are brought together.

5

WILLIAM P. CAMERON.
